UNITED STATES PATENT OFFICE.

ADOLPH LEMKE, OF MINNEAPOLIS, MINNESOTA.

CHIMNEY.

SPECIFICATION forming part of Letters Patent No. 593,303, dated November 9, 1897.

Application filed March 29, 1897. Serial No. 629,653. (No model.)

To all whom it may concern:

Be it known that I, ADOLPH LEMKE, a citizen of the United States, residing at Minneapolis, in the county of Hennepin and State of Minnesota, have invented certain new and useful Improvements in Chimneys; and I do hereby declare the following to be a full, clear, and exact description of the invention, such as will enable others skilled in the art to which

10 it appertains to make and use the same.

My invention has for its object to provide an absolutely fireproof chimney or stack for use in dwellings or other buildings.

To those who have given attention to the 15 subject, it is well known that a large percentage of the fires in buildings originate from defective chimneys or flues. The ordinary brick or other masonry chimney is not reliably fireproof. Under the unequal expansion and 20 contraction due to the wide range in temperatures to which the chimney is liable and the presence or absence of frost or moisture in the walls, the brick will crack and the mortar will break or crumble. The result is that cracks 25 or openings through the chimney almost inevitably occur in a short time after use. This is especially liable to be the case when the chimney itself takes fire on account of the accumulated soot therein. One of the principal causes which produces these cracks or 30 openings is the vapor which accumulates in various openings behind the chimney, producing confined pressure, which can only escape by a breakage in some of the surrounding walls. My invention has for its object to 35 overcome all these defects by the production of a chimney or stack which is reliably and absolutely fireproof.

To these ends my invention consists of the 40 novel devices and combinations of devices hereinafter described, and defined in the claims.

The invention is illustrated in the accompanying drawings, wherein, like letters referring to like parts throughout the several views—

Figure 1 is a perspective view with some parts broken away, illustrating the preferred form of my improved chimney or stack. Fig. 45 2 is a cross-section on the line $x^2 x^2$ of Fig. 1. Fig. 3 is a vertical section of the lower part of the chimney or stack on the line $x^3 x^3$ of

Fig. 2. Fig. 4 is a diagonal section through the corners of the upper part of the stack or chimney. Fig. 5 is a cross-section on the line 55 $x^6 x^6$ of Fig. 3. Fig. 6 is a perspective view of one of the sections of the inside or smoke stack detached with a part broken away. Fig. 7 is a similar view of one of the sections of the outside or protecting stack detached 60 with a part broken away.

My improved chimney or stack is made up of an inside member or smoke-stack proper and an outside or protecting stack, with the two members so related as to afford airways 65 between the two when in working position. Both members are made up of sections of fire-clay tiling. The sections of the inside member are marked on the drawings with the reference-letters $a^1 a^2$, &c., and the sections of 70 the outside member are marked with the reference-letters $b^1 b^2$, &c., counting from the base members upward. The sections of the inside member are preferably made of circular form in cross-section and the sections of 75 the outside member are preferably made of rectangular form in cross-section, as best shown in Figs. 2 and 5 of the drawings. In virtue of these relative shapes air ways or spaces c will be afforded at the corners between the inside members and the outside members when the said members are in working position in respect to each other. The sections of both members are provided with mortises f at one end and tenons f' at the 80 other for connecting the adjacent sections with a tight joint. The tenons f' are metallic, being preferably made of wrought-iron. The joints between the sections are also sealed with fire-clay cement when the sections are 85 put together. The sections of the inner member are bound together against endwise displacement by staple-like metallic keepers h , adapted to lap the joints and to be driven into the bodies of the bound sections. These keepers h are located in such positions as to abut 90 against the inside surfaces of the walls of the outer member and be thereby held from displacement. The sections of the outer member are united by staple-like keepers k , which 95 lap the joints and extend through the walls of the bound sections and secured from displacement by nuts k' , engaging the threaded stems of said staple-like keepers.

The two stack members are provided with a common cap p with double walls at its lower portion for coöperation with the adjacent sections of the inner and outer stack in the same way as the other sections of the respective stacks, with the exception that the airways p' therein converge inward and tap the outlet-opening p^2 of the cap, as clearly shown in Fig. 4.

- 10 The lower sections a' and b' , respectively, of the two stacks differ in certain details from the intermediate sections, as required for adaptation to catch and remove the soot and ashes from the stack. For this purpose the 15 base-section a' of the inner stack is provided with a series of radial openings $r r'$, of which the member r' is of larger size than the members r . Directly opposite the radial hole or opening r' in the base-section a' of the in- 20 side stack the base-section b' of the outside stack is provided with a similar opening r^2 , which is covered by a suitable door r^3 . Inside the base-section a' of the inside stack is preferably located an ash bucket or receptacle r^4 , provided with a series of pivoted slides r^5 near its bottom and directly opposite the radial openings r in the stack-section a' , and also provided with an opening r^6 , directly in line with the openings r' and r^2 in 25 the stack members a' and b' , respectively. The valves r^5 are normally closed, but may be opened whenever it is desired to reach through the radial holes r for cleaning out the lower ends of the airways c in case any 30 soot should accumulate therein. It is of course obvious that access may be had to the ash bucket or receptacle r^4 through said passages r' and r^2 in the stack members a' and b' when the door r^3 is opened.
- 35 At t in Figs. 1 and 2 is shown a thimble worked through suitable coincident holes in the two stacks for the application of a flue-pipe. When such a thimble is applied, the joint between the same and the stack members is sealed with fire-clay cement.
- 40 The two stack members are built up concurrently step by step. Otherwise stated, the base member a' of the inside stack, or the base member b' of the outside stack, as preferred, 45 is first located. Then the second member a^2 of the inside stack is applied in position on the base member a' , the keepers h having been previously attached at their lower ends to the base member a' and sprung or bent 50 outward sufficiently far to permit the second section a^2 to be jointed to said base-section a' . The upper ends of said keepers h are then bent inward and driven into the said section a^2 . The second section b^2 of the outside stack 55 is then slipped over the second section a^2 of the inside stack, and the binding-keepers k are applied and made fast by the nuts k' . These steps are repeated over and over again 60 in substantially the same order until the stack is completed.

65 From the foregoing description it is obvious that my improved stack is made up of fire-

proof material throughout, that the joints between the sections of both stacks are lapped by the joint irons or tenons f' and are sealed with fire-clay cement, that the sections are bound together against endwise displacement by metallic keepers, and that the two stack members are so related as to afford airways c between the two stacks, extending their entire length from base to cap and uniting at their tops with the outlet p^2 in the cap p of the chimney. In virtue of this construction it is hardly possible for the inside or smoke stack to become seriously affected with frost or moisture, and whatever amount of sweating therefrom may occur cannot result in the cracking of the same, for the reason that the airways c between the two stacks afford a ready outlet for the vapors therefrom. In virtue of the fact that the inside stack touches the walls of the outside stack at the tangents thereto it is obvious that the inside stack will be firmly braced and held in its upright position by the outside stack. The outside stack in virtue of its shape will be very firm and solid. Hence the inside stack will be absolutely free from any racking strains, except such as might affect the outside stack, which is something that would be difficult to do. It is thought, therefore, that the improved chimney herein disclosed is absolutely fire-proof under any and all conditions. No difference how great or sudden the change in temperature might be cracks or openings could hardly occur on account of the air-jacket between the two stacks and the outlets afforded for the vapors by the airways c . If the chimney should take fire on account of the accumulated soot therein, the same could do no damage below the outlet of the chimney, for the reason that the fire would be confined within the inside stack and could by no possibility heat the outside stack sufficiently to crack or break the same or set fire to any part of the building through which the outside stack passes. The airways c will afford so much relief to any hot air between the two stacks that the outside stack could hardly be broken by any degree of heat within the inside stack.

It should be further noted that the improved chimney above described is cheaper to make and more speedily built than the ordinary masonry chimney.

It will be understood that the details of the construction might be varied without departing from the spirit of my invention.

What I claim, and desire to secure by Letters Patent of the United States, is as follows:

1. A fireproof chimney or stack, made up of inside and outside members or sections, one class of which is round and the other class of which is square or polygonal in cross-section, which sections are built up one class inside of the other, with contact at certain points and vertical air-passages between the same, substantially as described.

2. In a double stack or chimney having air-

ways between the two, an ash bucket or receptacle at the bottom of the inside stack and openings through the two stacks for access to said bucket, substantially as described.

5 3. In a double chimney or stack, having air-ways between the two, an ash bucket or receptacle in the base-section of the inside stack having valves covering radial passages leading to said air-passages, and coincident openings in the base-sections of both stacks, for affording access to said ash-bucket, and a door controlling said opening, all substantially as described.

10 4. A fireproof chimney or stack made up of inside and outside hollow members or sec-

tions, formed with different cross-sections, at least one of which class of sections are polygonal in cross-section, said two classes of sections being built up, one inside of the other, and so related that they have contact 20 at certain points, but leave vertical air-passages between the same, substantially as described.

In testimony whereof I affix my signature in presence of two witnesses.

ADOLPH LEMKE.
